UNITED STATES PATENT OFFICE.

JOSEPH POLZIN, OF ROCK ISLAND, ILLINOIS.

WATER-HEATER.

1,244,775.

Specification of Letters Patent. Patented Oct. 30, 1917.

Application filed April 30, 1917. Serial No. 165,481.

To all whom it may concern:

Be it known that I, JOSEPH POLZIN, a citizen of the United States, residing at Rock Island, in the county of Rock Island and State of Illinois, have invented certain new and useful Improvements in Water-Heaters; and I do declare the following to be a full, clear, and exact description of the invention, such as will enable others skilled in the art to which it appertains to make and use the same.

My invention has for its principal object to provide a simple and inexpensive, yet a highly efficient water heating device for application to washing machines, bath tubs, water tanks, registers, etc.

A further object is to so construct the device as to permit the use thereof for supporting and heating numerous kinds of containers or cooking utensils.

With the foregoing general objects in view, the invention resides in the novel features of construction to be hereinafter fully described and claimed, the descriptive matter being supplemented by the accompanying drawings which form a part of this specification, and in which:

Figure 1 is a side elevation showing the application of the invention to a washing machine;

Fig. 2 is a bottom plan view of the heater with the burner and water circulating pipes detached;

Fig. 3 is a horizontal section on the plane of the line 3—3 of Fig. 1; and

Figs. 4 and 5 are vertical sections on the planes of the lines 4—4 and 5—5 respectively of Fig. 2.

In the drawings above briefly described, the numeral 1 has reference to a flat horizontal top plate which is preferably though not necessarily of rectangular formation, the under side of said plate being provided with a pair of spaced parallel hollow ribs 2 and 3 which form therewith an inlet and an outlet conduit. Additional parallel ribs 4 are formed on the lower side of the plate 1 and form with said plate a plurality of branch conduits extending between the inlet and outlet conduits and communicating therewith. The several ribs are by preference cast integrally with the top plane 1, but in some types of the device, said ribs could well be stamped from sheet metal and brazed or otherwise secured in place. In either case, the several ribs will by preference be V-

shaped in transverse section although this particular shape is not essential. The construction described forms a plurality of parallel heat pockets 5 between the ribs 4, which pockets are closed at their ends by the ribs 2 and 3. This arrangement insures effective heating of the several hollow ribs so that the water circulating therethrough will be raised quickly to a high temperature.

One end of the rib 2, and the other end of the rib 3, are formed with openings in which inlet and return pipes 6 and 7 respectively are tapped, these pipes being connected to the container of the water to be heated and thus serving to support the entire heating device. The particular location of the pipes, that is, at diagonally opposite corners of the plate 1, insures that the latter shall not tilt. It therefore forms an effective hot plate for supporting numerous kinds of containers 8 whereby the contents thereof may be heated.

A burner 9 is located beneath the ribs of the plate 1 and may be constructed to consume any kind of fuel, such as gas, kerosene, crude oil, alcohol, gasolene, etc. Burner 9 is provided with a horizontal supply pipe 10 passing through an opening 11 in a vertical arm 12 and clamped in said opening by a set screw or the like 13. Arm 12 preferably depends from the rib 2, and if the entire device be made of a casting as shown in the drawings, said arm will be formed integrally with this rib.

In applying the improved heater, the two pipes 6 and 7 are connected with the container whose contents are to be heated, said pipes communicating with said container at comparatively low and high levels, respectively. The water thus enters the heating device through pipe 6 and after being heated, rises from said device through the pipe 7. Continuous circulation is maintained as long as the burner is in operation, with the result that the water will be heated in a short length 100 of time. As above suggested, the burner is applicable for a great number of uses, but for illustrative purposes, I have shown the same applied to a common type of washing machine. Regardless of its application, however, the device will be highly efficient, and due to its construction, will be a convenient means of heating the contents of utensils or the like by placing them on the plate 1 as indicated in Fig. 1. On account 110 of the advantages derived, the specific construction shown and described constitutes

the preferred form of the improved heater, but I wish it understood that within the scope of the invention as claimed, numerous minor changes may be made without sacrificing the principal advantages.

I claim:

1. A water heating device comprising a top plate, a pair of spaced hollow ribs on the under side of said plate and forming therewith an inlet and an outlet conduit each having means at one end for connecting a circulating pipe thereto, additional hollow ribs on the under side of said plate, said additional ribs forming with said plate a plurality of branch conduits extending between and communicating with said inlet and outlet conduits, and a burner beneath said plate and ribs.
2. A water heater comprising a top plate, a pair of spaced hollow ribs on the under side of said plate and forming therewith an inlet and an outlet conduit each having means at one end for connecting a circulating pipe thereto, additional hollow ribs on the under side of said plate and forming therewith branch conduits extending between and communicating with said inlet and outlet conduits, a vertical arm depending from one of said conduits and having an opening adjacent its lower end, a fuel

supply pipe passing through said opening, and a burner supported by said pipe and positioned for heating the several conduits.

3. A water heating device comprising a cast horizontal top plate of substantially rectangular configuration, a pair of hollow ribs cast integrally with the under side of said plate and located along opposite edges thereof, said ribs forming with said plate an inlet and an outlet conduit each having means at one end for the connection of a water circulating pipe, additional hollow ribs at right angles to the others and cast integrally therewith and with the lower side of said top plate, said additional ribs communicating with said first named ribs, a vertical arm cast integrally with one of said first named ribs and depending therefrom, said arm having adjacent its lower end an opening, a fuel supply pipe passing through and secured in said opening, and a burner supported by said pipe and positioned for heating the several ribs.

In testimony whereof I have hereunto set my hand in the presence of two subscribing witnesses.

JOSEPH POLZIN.
